Patented Oct. 12, 1915.

2 SHEETS—SHEET 2.

UNITED STATES PATENT OFFICE.

THOMAS FONTENOT, OF GED, LOUISIANA.

OIL-WELL RIG.

1,156,678.

Specification of Letters Patent.

Patented Oct. 12, 1915.

Application filed September 19, 1914. Serial No. 862,484.

To all whom it may concern:

Be it known that I, THOMAS FONTENOT, a citizen of the United States, residing at Ged, Calcasieu parish, and State of Louisiana, have invented certain new and useful Improvements in Oil-Well Rigs, of which the following is a specification.

The present invention relates broadly to an oil well rig, and more particularly to 10 that type of rig capable of performing the combined operations of drilling, pumping, and hoisting.

This invention has for its principal object improvements in oil well rigs, and particularly to means for connecting a single driver to either a spudding or hoisting mechanism.

A further object of this invention is to provide in an oil well rig of this nature a 20 novel means for varying the speed of the hoisting drum.

A still further object is to provide a variable speed gearing for the operation of the apparatus, in which the changing of the 25 speed can be accomplished substantially without clashing, and in which shocks incident to the change, acceleration or diminution of the speed of the driven shaft, are kept at a minimum.

Other and further objects of the invention will in part be obvious and will in 30 part be pointed out in the specification hereinafter following, in which like characters are used to represent like parts throughout 35 the several views thereof.

Referring specifically to the drawings: Figure 1 is a perspective view of the oil 40 well rig. Fig. 2 is a side view of the structure shown in Fig. 1, with one of the standards removed. Fig. 3 is an enlarged detail view of one of the clutches employed.

With devices of this nature now in use it is customary to provide separate attachments for both the pumping and drilling 45 operations. Such a construction necessitates a large number of parts, and necessarily requires a great deal of adjusting and shifting of the driving connections for these parts. By the present invention the applicant obviates all of these objections, and 50 provides a compact rig which effectually performs all of these operations.

Referring now to the drawings, the improved rig comprises a pair of side standards 1 and 2, between which is rigidly secured a base block 4. Extending trans-

versely of the base block, and across the tops of the standards adjacent the ends thereof are braces 5 and 6. The brace 5 is provided on one side with an extension 7. 60

A main drive shaft 8, mounted in suitable bearings 9 on each of the standards, extends transversely of the frame. Splined, or otherwise secured upon the shaft 8, is a main drive sprocket 10 having a sprocket chain 11 connected with any suitable source of power (not here shown).

For connecting the driving mechanism with the spudding or pumping apparatus, there is provided a gear wheel 12, which is loosely mounted on the shaft 8 and adapted to rotate freely thereon. A complementary gear wheel 14 keyed upon the countershaft 15 is in alinement and constantly in mesh with the gear 12. Suitable bearings 16 upon the standard 2 and the extension 7 are provided for the counter shaft. On the inner end of the counter shaft there is secured a bevel gear 17 of relatively small diameter, which transmits power to the pumping or 70 drilling shaft 18. This shaft extends longitudinally of the frame and is carried in bearings 19 secured to each of the cross braces 5 and 6. In operative connection with the bevel gear 17 is a large bevel gear 19 fixed to one end of the shaft 18. On the opposite end of this shaft is a wheel or arm 20 having a crank pin 21 eccentrically carried thereby. The pin 21 is provided for attachment to the pitman 22 of the pump. It is obvious that when the apparatus is to be used for drilling that a flexible link or its equivalent may be substituted for the pitman. 80

In order to operate the shaft 18 and its 90 associate parts from the main drive shaft, a clutch 24 is slidably splined to the drive shaft. This clutch is provided with engaging projections 25 adapted to be thrown into working engagement with the member 100 26 on the wheel 12. By reference particularly to Fig. 3 it will be seen that the clutch 24 has a groove 23 around its central portion. An operating lever 27 pivoted as at 28 upon any suitable support 29 is provided 105 with an inner bifurcated end extending into the groove 23, for sliding the clutch.

With devices of this nature it is frequently desirable to suspend the pumping or drilling operation, in order to remove 110 broken tools or foreign substances from the well. It is in this connection that the clutch

24 plays its most important part. This means for removing any desired object from the well is here shown as comprising a derrick 30 located at one end of the oil well 5 rig frame, having the usual sheave 31 for the cable 32. One end of the cable 32 passes around a bull wheel or drum 34 secured upon the shaft 35. Suitable bearings 36 are located upon the standards for receiving the ends of the shaft. For driving the bull wheel there may be provided a line shaft 37 above the drum shaft, and extending parallel therewith, and having bearings 38. A sprocket wheel 39 secured to the shaft, is driven by a chain 40 from the driving sprocket 41 loosely mounted upon the main drive shaft. The sprocket 41 has an engaging member 42 upon one face for engagement with the projections 44 of the clutch 24.

As it is frequently desirable and necessary to drive the bull wheel at varying speeds, a change speed mechanism is provided upon the shaft 35. This comprises a large 25 sprocket wheel 45, and a smaller wheel 46 spaced a suitable distance therefrom, both of the sprockets being loosely carried upon the shaft 35. The adjacent faces of the wheels 45 and 46 are provided with clutch 30 engaging members 47 and 48, respectively, adapted to slidably receive the clutch 49 mounted between them and operated by any suitable lever 50. The clutch 49 is identical with that shown in Fig. 3, and will not be 35 fully described at this point. Rigidly secured to the line shaft 37 is a pair of sprockets 51 and 52 in alinement respectively with the sprockets 45 and 46, and having respective driving connections 54 and 55 with the 40 drum shaft. By this arrangement it is possible to readily shift from one speed to another without touching the main clutch mounted on the drive shaft.

For lowering any desired material into 45 the well it is necessary to employ a suitable brake for controlling the speed of the bull wheel and preventing damage to the rig due to racing. A desirable brake for use in this connection is shown as comprising a 50 lever 56 pivotally carried by a bracket 57.

A flexible steel brake shoe passes around the brake drum 58 which is secured to one head of the bull wheel. By moving the lever outwardly it is apparent that the friction between the shoe and the brake drum will be 55 increased, thereby providing means for easily regulating the run of the cable.

For allowing the bull wheel to rotate freely, I have shown the base block terminating at a point considerably at one side 60 thereof.

While I have shown and described the most desirable form of my invention, it is apparent that changes in the details thereof 65 may be made without departing from the spirit and scope of this invention.

Having thus described my invention what I desire to claim is:

1. A combined hoisting and spudding apparatus comprising a pair of side members, a main drive shaft extending transversely between said members, a drilling shaft extending longitudinally of said side members, a counter shaft provided with means for operating said drilling shaft from 70 the drive shaft, a hoisting mechanism, and means for operatively connecting either said hoisting mechanism or said drilling shaft to the main drive shaft. 75

2. A combined hoisting and spudding apparatus comprising a pair of side members, a main drive shaft extending transversely between said members at one end thereof, a drilling shaft extending longitudinally of said side members, a counter shaft above 80 said drive shaft provided with means for operating said drilling shaft from the drive shaft, a hoisting mechanism at the opposite end of said members, means for operatively connecting either said hoisting mechanism 85 or said drilling shaft to the main drive shaft, and a variable speed transmission device for controlling the speed of the hoisting mechanism. 90

In testimony whereof I have hereto subscribed my name.

THOMAS FONTENOT.
